COMBINED HINGE AND DOOR CHECK

Edward L. Ackerman, Detroit, Mich., assignor, by
mesne assignments, of one-fourth to Edward
L. Ackerman, one-fourth to Clarence E.
Blaesser, one-fourth to Chester T. Fezzy, and
one-fourth to Alois J. Zwierzina, all of Detroit,
Mich.

Application December 23, 1937, Serial No. 181,268

1 Claim. (Cl. 16—135)

This invention relates to a combined hinge and door check particularly adaptable for use in conjunction with doors of automotive vehicle bodies.

5 The object of the invention is to provide a hinge element having a hinged leaf provided with an arm carrying a stop and means associated with the arm to provide a check to releasably hold the door in a predetermined open 10 position as is disclosed in my U. S. Letters Patent No. 2,147,133, issued Feb. 14, 1939.

In automotive vehicle bodies, especially if the vehicle be standing on an incline or if there be a wind blowing, an open door tends to swing to a closed position thus interfering with the occupants in getting in or out of the vehicle and the ready removal of articles carried in the body. The door check and stop is here shown as provided in association with a hinge of the concealed 20 type wherein the hinge member itself is wholly enclosed within the sheet metal door pillar of the automobile body when the door is in the closed position and thus the door check is positioned within the walls of the body and thus is not obtrusive or even visible either interiorly or exteriorly of the body.

A further feature of the invention is to provide a bar carried by the hinged leaf attached to the door and movable through a member having a slot as the door is opened or closed the bar having a recess formed in one face to receive a spring pressed ball carried by the slotted member and riding the surface of the bar so that as the door is swung toward open position the ball automatically engages in the recess and releasably sustains the door in an open position.

These and other features and object of the invention are hereinafter more fully described and claimed, and the preferred form of construction 40 of a combined hinge and door check is shown in the accompanying drawing in which—

Fig. 1 shows the preferred form of construction of a hinge and door check in plan view and the association thereof with the door and the body framing of an automotive body.

Fig. 2 is a section taken on line 2—2 of Fig. 1 showing the door check bar and the releasable means for sustaining it in position.

Fig. 3 is a side elevation partly in section of 50 a portion of the door check.

The hinge as here shown is of the concealed type, it having a fixed leaf 1 attached to a wall 2 of a sheet metal pillar element 3 and a hinged leaf 4 attached to a door element indicated at 55

connected by a gooseneck 6 which extends through an aperture 7 in a wall 8 of the pillar facing the door edge, the fixed leaf 1 being introducible through the opening 7 and attached to the wall 2 of the pillar. The gooseneck portion is so formed and positioned that, as the door is swung to the open position as indicated by the dotted lines in Fig. 1, the said gooseneck swings out through the aperture and straddles the edge of the pillar wall at the aperture and the associated outer 10 body panel 9.

The panel 9 is recessed at 10 and the door element has a flange 11 which extends into the recess and the outer wall 12 of the door is attached to said flange. While the inner panel wall of the vehicle body is not here shown, it is to be understood that the pillar 3 is positioned within the outer and inner walls of the body. In the hinge structure here shown, an eye 13 is provided on the outer face of the bend of the gooseneck 6 and to this eye is pivoted a bar 14 of arcuate form which extends through an aperture 15 in the wall 2 of the pillar and also through an aperture provided in a striker plate 16 attached to the wall 2 and preferably by the screws 15 by which the fixed leaf 1 is attached to the opposite face of the wall. The plate 16 at one end is formed with a face 18 that lies at an angle less than a right angle to the outer wall panel 9 in the section shown, the purpose of which angular face 30 18 is hereinafter described. This plate 16 has an aperture 19 having inner and outer side walls oppositely curved as will be understood from Fig. 1. The bar 14 of the door check rides in the aperture and, as the door is swung outwardly from the full line position shown to the dotted line position, the inner and outer side edges of the check bar 14 ride somewhat closely to the curved side walls of the aperture 19 and then the bar 14 is held at all times from material 35 lateral displacement as will be readily understood from the drawing.

The outer end of the bar 14 is provided with a threaded shank 20 to the end of which is threaded the nut 21 having a flange 22. The 45 nut may be of the castellated type and secured in position by a cotter pin indicated at 23. The washer face 22 is preferably recessed to receive an end of a rubber bumper or stop 24. This stop 24 cushions the door in swinging it to the 50 full open position as the opposite end of the stop engages the face 18 of the plate 16 and prevents too sudden a jar being imposed on the hinge elements.

It is a feature of this invention to provide 55

in addition to a stop a means for checking the door and releasably sustaining it in an open position. For this purpose, I provide a preferably coned notch 25 in the under face of the bar 14. 5 The plate 16 has a vertical recess 26 therein and through which the slot 19 extends at a right angle. On the under side of the bar 14 in the recess is positioned a ball 27 urged to contact with the bar 14 by a coiled spring 28. Thus 10 when the door is swung to a nearly full open position, the ball 27 will seat in the notch 25 and sustain the door against any ordinary tendency to swing to closed position as by gravity or wind pressure but the operator may readily move 15 the door from this position as the ball will readily retract from the coned recess 25 to permit such action.

It is also sometimes desirable to have more 20 than one recess for the ball. I have shown such recess at 29 and from Fig. 3 it will be observed that this recess is indicated as being of less depth than the recess 25 and when the ball engages in the recess 29, the door is movable from such 25 position more readily than is the case when the ball is seated in the deeper recess 25. Thus the door may be checked at any desirable open position other than the practically full open position for which purpose the deeper notch 25 is provided.

30 It will be noted that as the door is swung to full open position, the inner face 30 of the bumper or stop member 24 is brought to engagement with the angular face 18 of the plate 16 in which position the face of the stop and the 35 angular face 18 are in parallel relation. The face 18 will differ in its angular disposition, depending upon the exact structures on which the member 16 may be mounted but in any arrangement the face 18 should be parallel with the inner face 30 of the bumper member 24 when 40 the door is swung to its full open position in order that the pressures may be properly taken by the bumper element.

From the foregoing description, it is believed 45 evident that the various objects and features of the invention are attained by the structure described; that the described door stop and check may be used with hinges other than the con-

cealed type as shown, and that various changes may be made in the structure without departing from the spirit and scope of the invention as set forth in the appended claim.

Having thus fully described my invention, its 5 utility and mode of operation, what I claim and desire to secure by Letters Patent of the United States is—

A combined hinge and door check for the doors of automobile bodies having a hollow sheet metal pillar at one edge of the door opening, comprising a fixed leaf secured to the inner face of the wall of the pillar opposite the side thereof facing the door opening, and a hinged leaf attached to the door adjacent the pillar, the wall of the 10 pillar facing the door opening having an aperture, a gooseneck attached to the hinged leaf and extending through the said aperture in the pillar and pivoted to the fixed leaf, a plate secured to the outer face of the pillar wall to 15 which the fixed leaf is attached and having an aperture substantially in registration with an aperture provided in the said last named wall of the pillar, the plate aperture being of greater width at the plate surfaces than at the center, 20 a door check and a stop comprising a bar movable through the said registering apertures in the plate and wall of the pillar and having its inner end pivoted to the gooseneck at the bend thereof, 25 said bar being arcuate in form and being moved through the said registering apertures on an arc as the door is swung to open position, the greater width of the aperture in the plate at its surfaces and less width at its center holding 30 the arm from lateral displacement while permitting the same to move on an arc without binding in the aperture, said plate having a recess extending substantially at a right angle to the aperture and opening thereto substantially centrally thereof on the under side of the bar, 35 a spring pressed ball in the said recess, the bar having a recess to receive the ball as the door is swung to open position to thereby releasably sustain the door, and a bumper carried by the 40 bar and engageable with the apertured plate 45 when the door is swung to full open position.

EDWARD L. ACKERMAN.
